UNITED STATES PATENT OFFICE.

EMIL J. WESP, OF ROCHESTER, NEW YORK.

FASTENER FOR HEELS.

1,119,556.

Specification of Letters Patent.

Patented Dec. 1, 1914.

Application filed October 21, 1912. Serial No. 727,079.

To all whom it may concern:

Be it known that I, EMIL J. WESP, a citizen of the United States, residing at Rochester, in the county of Monroe and State of 5 New York, have invented certain new and useful Improvements in Fasteners for Heels, of which the following is a specification.

The object of this invention is to provide 10 a cheap, strong and effective fastener by which wooden heels may be readily and securely fastened to shoes.

In the accompanying drawings Figure 1 15 is a perspective view of a shoe partly broken away, showing the method by which the fastener is held in place. Fig. 2 is a perspective view of a shoe partly broken away, with the heel removed therefrom, showing the fastener in place thereon. Fig. 3 is a perspective of the heel with a small metal strap 20 fastened thereon. Fig. 4 is a sectional view of a shoe, the section being taken on the line 4^x—4^x in Fig. 1. Fig. 5 is a perspective view of the fastener alone. Fig. 6 is a plan view 25 of the blank from which the fastener is formed.

In the accompanying drawings like reference numerals refer to like parts.

In the drawings reference numeral 1 indicates a shoe having the upper 2, the outer sole 3, the inner sole 4 and the heel 5. The outer sole 3 is partly cut away as shown in Fig. 2, and extends in over the heel. The insole 4 extends over the heel and outer sole, 35 which is partly cut away, being inclosed between the inner sole and the heel.

Attached to the rear of the shoe as shown in Fig. 2, is the fastener 6. This fastener is formed from the blank 9 shown in Fig. 6. 40 From this blank are bent up the two prongs 7 and 8, while the central part of the blank is bent down and under to form a hook. The fastener is applied to the outer and inner sole, the prongs 7 and 8 being passed up 45 through suitable perforations in the inner and outer sole and then bent down as shown in Figs. 1 and 4 so as to firmly hold the hook in place.

The heel is attached in the following manner: fastened with nails 10 and 11 to the rear end of the heel as shown in Fig. 3, is a 50 small metal strap 6^a, which strap is flared

upwardly at the rear in the middle. The heel with this metal strap fastened thereon is hooked onto the fastening on the shoe, the attachment of the heel to the shoe being completed by the use of the nails 12 and 13, which are driven through the inner and outer sole onto the heel. To complete the fastening of the heel, glue may be used instead of nails, or both glue and nails may be used. The inner sole with its nails and prongs exposed therein, is covered with a bottom lining or heel pad which is ordinarily used in shoes.

It will be understood that the heel which is fastened to the shoe in the manner described is made preferably of wood, such heels being preferred for certain styles of shoes, the heels being covered with any kind 70 of material to match the upper of the shoe.

Having thus described my invention, what I claim as new and patentable is as follows:

1. The combination in a shoe, of an upper having an outer sole and an inner sole, said outer sole being partially cut away at the rear, a heel for said shoe, said heel fitting the cut-away portion of the outer sole, a strap fastened to the top of the heel, and a fastener at the rear of the outer sole to engage 80 said strap and thereby join the heel to the shoe, said fastener having upwardly extending prongs to pass through and engage with the inner sole and the outer sole and having a prong on the end extending 85 downwardly and forwardly to engage with said strap.

2. The combination in a shoe having an inner sole and an outer sole, said outer sole being partially cut away at the rear and 90 said sole provided with perforations, a heel fitting the cut-away portion of the outer sole, a fastener having a pair of prongs to be passed through said perforations and bent outwardly above the inner sole, said 95 fastener having a third prong extending downwardly and forwardly from its end, and a heel having a fastening member to be engaged by said third prong to thereby join the heel to the shoe.

3. The combination in a shoe having an outer sole and an inner sole, and a heel attachable to the shoe, of co-acting fastenings between the heel and outer sole, one of said

fastenings being secured to the heel, and the
other fastening comprising a plate having
a pair of oppositely-disposed prongs to be
passed through said inner and outer sole,
and having a third prong extending down-
wardly and forwardly to engage said heel
fastening.

In testimony whereof I affix my signature
in presence of two witnesses.

EMIL J. WESP.
